WRITING PEN CAP

Guy A. Taylor, Batavia, Ill., assignor to Sanford Research Company, Bellwood, Ill.

Filed Aug. 8, 1973, Ser. No. 386,512

Term of patent 14 years

Int. Cl. D19—06

U.S. Cl. D19—57

FIG. 1 is a side elevational view of a writing pen cap showing my new design;

FIG. 2 is a left end elevational view;

FIG. 3 is a right end elevational view;

FIG. 4 is a top plan view; and

FIG. 5 is a bottom plan view thereof.

I claim:

The ornamental design for a writing pen cap, as shown.
